UNITED STATES PATENT OFFICE.

GEORGE HENRY WHEARY, OF RACINE, WISCONSIN.

CONVERTIBLE TRUNK.

1,314,556.

Specification of Letters Patent. Patented Sept. 2, 1919.

Application filed August 10, 1916. Serial No. 114,125.

To all whom it may concern:

Be it known that I, GEORGE HENRY WHEARY, a citizen of the United States, and resident of Racine, in the county of Racine and State of Wisconsin, have invented new and useful Improvements in Convertible Trunks, of which the following is a description, reference being had to the accompanying drawings, which are a part of this specification.

The invention relates to improvements in convertible trunks.

In wardrobe trunks the body portion of the trunk is usually divided into two sections vertically and one of these sections is provided with drawers for holding various articles of apparel. One or two of the drawers are usually used for holding hats and as hats vary in size, to a large extent it is very difficult if not impossible practically, to provide a single drawer which will accommodate the various sizes of hats.

It is one of the objects of the present invention to overcome the before mentioned objectionable features and provide a convertible trunk in which the drawers are so constructed that one may be inverted and combined with the drawer below to form a hat case of the size of both drawers combined.

A further object of the invention is to provide a convertible trunk having a plurality of drawers which may be combined to form one case, or may be used independently as single drawers.

A further object of the invention is to provide a convertible trunk in which the front portion of one of the convertible drawers is detachably connected to the drawer to permit convenient access to both drawers when combined together.

With the above and other objects in view the invention consists of the improved convertible trunk and its parts and combinations as set forth in the claims, and all equivalents thereof.

In the drawing in which the same reference characters indicate the same parts in all of the views:

Figure 1 is a front view of the drawer section of a wardrobe trunk provided with the improved convertible feature, the trunk being shown in open position and the wardrobe section and the top cover being indicated by dotted lines;

Fig. 2 is a vertical sectional view thereof

taken on line 2—2 of Fig. 1, a portion of the convertible drawer being indicated in partly open position by dotted lines;

Fig. 3 is a vertical sectional view similar to Fig. 2 with the convertible drawer shown in inverted position;

Fig. 4 is a transverse sectional detail view taken on line 4—4 of Fig. 1; and

Fig. 5 is a transverse sectional detail view taken on line 5—5 of Fig. 1.

Referring to the drawing the numeral 10 indicates a convertible wardrobe trunk, 11 the wardrobe section, 12 the drawer section thereof which is provided with a compartment 13 to receive the improved convertible hat case or drawer 14 and drawers 15 and 15'. The convertible hat case or drawer is open at its top and while preferably positioned directly above the lowermost drawer 75 may be positioned, in connection with a co-acting lower drawer, at any point desired. The said convertible drawer is supported on angle ways 16 fastened to the side walls of the compartment and when used as an ordinary drawer is free to be withdrawn from the compartment. The front wall 17 of the casing 14 is detachably connected to the casing proper by angular side edge plates 18 and a spring actuated bolt member 19 carried by the wall. The angular side edge plates 18 are fastened to the inner side of the front wall adjacent its side edges and extend outwardly approximately the thickness of the wall and then extends at right angles as indicated by the numeral 20 to overlap the front side edges of the drawer and limit the inward movement of said front wall.

The forward side and bottom edge portions of the convertible drawer 14 are reinforced by angular guide strips 21 which also serve to guide and maintain the drawer centrally within the compartment. The bottom portion 22 of the convertible drawer is of less length than the side portions to form a groove or recess 23 between the front edge of the bottom portion 22 and the front upturned portion of the lower guide strip 21 to receive the lower edge portion of the front wall 17 as shown in Fig. 2.

The bolt member 19 extends transversely of the front wall 17 and comprises two slideable bolt rods 24 having inner angular ends 25 which extend outwardly through elongated slots 26 formed in the medial portion 27 of the bolt member 19. The medial mem-

- ber is provided with a coiled spring 28 which is interposed between the inner angular ends of the bolt rods 24 to hold said bolt rods yieldingly in locking position. The outer 5 ends 29 of said rods are beveled to provide for the automatic locking of said front wall when the wall is pushed inwardly to closed position. Apertured locking plates 30 fastened to the inner surfaces of the side walls 10 of the trunk section project outwardly therefrom and are engaged by the beveled ends of the bolt rods. Portions of the angular side edge plates 18 are recessed as indicated by the numeral 31 to accommodate the projecting ends of the locking plates 30.

All of the drawers are provided with handles 32 for convenience of the user.

- The drawer 15' is provided with hat pads 33 which are removably fastened to brackets 20 34 mounted on the front and rear walls of said drawer. When the convertible drawer 14 is in inverted position the pads 33 extend upwardly and partly into said inverted drawer and serve to lock said drawers together and prevent the possible injury to 25 hats within the drawer by pulling the drawers independently to open position.

The drawers may be independently used in the ordinary manner and when it is desired to combine the space of the two lower 30 drawers the convertible drawer is inverted and the pads of the lower drawer are positioned to lock the two drawers together. Access to the combined space is now had by 35 the front wall or cover of the convertible drawer and when this is unlocked by pressing the angular ends of the bolt rods together it may be removed. When removed hats may be removed through this opening 40 or the lower drawer may be pulled to open position. When the front wall or cover is closed and the pads are in the position both drawers are locked together and can only be pulled outwardly jointly.

- 45 From the foregoing description it will be seen that the convertible drawer is of very simple construction and is well adapted for the purpose desired.

What I claim as my invention is:

- 50 1. A convertible trunk, comprising a trunk section having a drawer compartment, drawers positioned one above another in said compartment, one of said drawers having an open front and being invertible to 55 form a single space when combined with the drawer beneath, a detachable front wall for said front opening, holding means mounted on the side edge portions of the front wall and which means bears against the front 60 edge portions of the drawers, and means for locking the front wall in closed position.

65 2. A convertible trunk, comprising a trunk section having a drawer compartment, drawers positioned one above another in said compartment, one of said drawers having

an open front and being invertible to form a single space when combined with the drawer beneath, a removable front wall for the front opening, angular strips mounted on the side edge portions of the front wall and 70 which strips bear against the front edge portions of the drawers, and locking means carried by the front wall and engaging the opposite sides of the compartment.

3. A convertible trunk, comprising a 75 trunk section having a drawer compartment, drawers positioned one above another in said compartment, one of said drawers having an open front and being invertible to form a single space when combined with the 80 drawer beneath, means for locking the convertible drawer to the drawer beneath when said convertible drawer is in inverted position, a removable front wall for the front opening, angular strips mounted on the side 85 edge portions of the front wall and which strips bear against the front edge portions of the drawers, and locking means carried by the front wall and engaging the opposite sides of the compartment. 90

4. A convertible trunk, comprising a trunk section having a drawer compartment, drawers positioned one above another in said compartment, one of said drawers having an open front and being invertible to form a 95 single space when combined with the drawer beneath, a removable front wall for the front opening, angular strips mounted on the side edge portions of the front wall and which strips bear against the front edge 100 portions of the drawers, a locking means carried by the front wall and engaging the opposite sides of the compartment, and means for locking the convertible drawer in inverted position to the drawer beneath, said 105 locking means permitting the independent movement of the drawer beneath the convertible drawer when the front portion of said convertible drawer is removed.

5. A convertible trunk, comprising a trunk 110 section having a drawer compartment, drawers positioned one above another in said compartment, one of said drawers having an open front and being invertible to form a single space when combined with the 115 drawer beneath, a removable front wall for the front opening, angular strips mounted on the side edge portions of the front wall and which strips bear against the front edge portions of the drawers, apertured 120 locking plates mounted on the opposite side walls of the compartment and projecting forwardly therefrom, a locking means carried by the front wall and engaging the locking plates of the opposite sides of the 125 compartment, and means for locking the convertible drawer in inverted position to the drawer beneath, said locking means permitting the independent movement of the drawer beneath the convertible drawer when 130

the front portion of said convertible drawer is removed.

6. A drawer for a convertible trunk, comprising a casing having an open top and front portion and a groove provided in its lower front edge portion, a removable front for the open front portion having its lower edge portion entering the groove, angular strips mounted on the opposite side edges of 5 the removable front and which strips bear 10 against the front edges of the opposite sides

of the casing, apertured locking plates mounted on the opposite side walls of the container, bolt rods slidably mounted on the removable front and having beveled outer 15 ends which lockingly enter the apertures of the locking plates, said bolt rods having adjacent outwardly projecting handle portions, and a yielding means for holding the bolt rods in locking position. 20

In testimony whereof, I affix my signature.
GEORGE HENRY WHEARY.
